UNITED STATES PATENT OFFICE.

ANTHONY NAMOLICK, OF SCRANTON, PENNSYLVANIA, ASSIGNOR OF ONE-HALF TO
JOHN GRATKOWSKI, OF SCRANTON, PENNSYLVANIA.

AUTOMATIC RAILROAD-CROSSING GATE.

1,360,139.

Specification of Letters Patent. Patented Nov. 23, 1920.

Application filed September 30, 1919. Serial No. 327,446.

To all whom it may concern:

Be it known that I, ANTHONY NAMOLICK, a citizen of the United States, residing at Scranton, in the county of Lackawanna and 5 State of Pennsylvania, have invented certain new and useful Improvements in Automatic Railroad-Crossing Gates, of which the following is a specification.

The primary object of the present invention resides in the provision of an automatic railroad crossing gate that is adapted to be operated by a train moving over the track with the gates maintained in lowered closed positions while the train is passing the cross-over and being automatically returned to their open positions after the train has passed beyond the cross-over as soon as the train has passed a certain distance beyond the cross-over.

With the above general objects in view and others that will appear as the nature of the invention is better understood, the same consists in the novel construction, combination and arrangement of parts hereinafter 25 more fully described, illustrated in the accompanying drawings, and pointed out in the appended claims.

In the drawings forming a part of this application and in which like designating 30 characters refer to corresponding parts throughout the several views,

Figure 1 is a top plan view of a railroad track with the present invention in operative position relative thereto,

Fig. 2 is a side elevational view of the same with the operating mechanism for the gate arms shown in dotted lines,

Fig. 3 is a longitudinal sectional view of a portion of a track with the housing embedded in the ground within the same for containing the operating mechanism for the crossing arms, the trip mechanism being shown in set position,

Fig. 4 is a view similar to Fig. 3, showing the trip mechanism engaged by a car wheel and having operated the crossing arm mechanism,

Fig. 5 is a longitudinal sectional view of the track similar to Fig. 3, and taken at the 50 opposite end of the operating mechanism, both crossing arms being shown in vertical position,

Fig. 6 is a view similar to Fig. 5, showing the crossing arms in lowered closed position

with the forward trip engaged by a car 55 wheel,

Fig. 7 is a vertical cross sectional view of one of the stands supporting a crossing arm and also illustrating the cage for housing the operating mechanism, and

Fig. 8 is a view similar to Fig. 7, showing the modified form of the invention wherein the crossing arm is operated by meshing gears in lieu of a belt.

Briefly described, the present invention 65 aims to provide a railway crossing guard embodying vertically swinging crossing arms or gates positioned at opposite sides of a railroad track and having means associated therewith and operable by an approaching 70 train in either direction for operating the crossing arms to lower the same to their operative substantially closed positions while the train is passing the cross-over and which arms will be released for movement to 75 vertically inoperative positions after the train has passed the cross-over while traveling in either direction. The operating mechanism for the crossing arms embodies the provision of a longitudinal casing positioned beneath the track and having a plurality of shiftable arms connected at their ends to rotatable disk members with the end arms extending outwardly of the casing and having the outwardly projecting ends thereof 80 spring-pressed upwardly to position adjacent the rail treads for engagement by the 85 rolling stock and operation of the crossing arms.

Describing the invention more in detail 90 there is illustrated a railroad track embodying opposite rails 9 supported upon ties 10, the rails and ties being of ordinary construction while a pair of vertical casings 11 are arranged at opposite sides of the rails 95 9 at the point of a cross-over and have rotatably supported exteriorly thereof crossing arms 12 having counterweights 13 at their inner ends for purposes presently to appear.

A longitudinally extending housing 14 100 substantially rectangular in cross section is arranged beneath the ties 10 and is provided with a removable cover wall 15 supported upon flanges 16 as clearly illustrated in Fig. 7, the housing 14 extending a considerable distance at each side of the cross arms 12, one end thereof being shown

in Figs. 3 and 4 while the opposite end is shown in Figs. 5 and 6. The lower ends of the casings 11 are embedded in the ground and are connected to the housings 14 by 5 tubular members 17 through which a rotatable shaft 18 extends, the shaft passing through a bushing 19 inwardly of the housing 14 and journaled at its end in the bearing 20 while the other end of the shaft 18 10 is secured to the transverse bearing 21 axially alined therewith and positioned within the casing 11. The shafts 18 are associated respectively with the lower end of each casing 11 and extend from a point 15 within each housing 14 transversely of the track and journaled upon each shaft within said housing, is a disk 22, the disks 22 being fixed to and rotatable with the shafts 18 and being connected by a link 23 pivotally connected at its ends as at 24 to the 20 inner and outer sides respectively of the disks 22, so that upon rotation of one disk 22 similar movement will be communicated to the other disk. The mechanism for rotating the disks 22 includes a second disk 25 journaled upon the transverse shaft 26 extending across the housing 14, the disk 25 being connected by a link 27 to the disk 22 while an operating lever 28 connected to the 25 disk 25 diametrically opposite the connection of the link 27, extends through an end opening 29 provided in the end wall of the housing 14 and carrying a trip 30 upon its projecting end lying adjacent the rail 30 9 of the track. The lever 28 is held in its uppermost position with the trip 30 slightly spaced above the rail 9 by a pin 31 resiliently mounted as at 32 in a socket provided in the adjacent enlarged end of said housing, this 35 construction being clearly shown in Figs. 3 and 4. The opposite end of the housing 14 is similarly constructed with a pin 31 tensioned as at 32 while the lever 28 is directly engageable with the adjacent disk 22 and projects through the end opening 29 40 in the housing 14 and carries a trip 30 upon the projecting end thereof.

Rotary motion is communicated from the shafts 18 to the crossing arms 12 and by 45 devices shown more clearly in Fig. 7, there being illustrated a transverse bearing 33 in which is journaled a shaft 34, for supporting the cross-arm 12, a pulley 35 being secured to the shaft 34 within the casing 11 50 and having a belt connection 36 with the lower pulley 37 carried by the shaft 18 within the bearing 21.

A modified form of the invention is shown 55 in Fig. 8, wherein a plurality of meshing gears 38 journaled within the casing 11 communicates motion from the crank shaft 39 to the crossing arm 12, an arm 28' similar to the lever 28 being connected to the crank shaft 39 and operable by a like trip mechanism for shifting the crossing arms.

A lamp-post 41 illustrated in Figs. 1 and 2 is provided and carries an illuminating burner of any desired character with a danger sign positioned therebeneath while an electric bell 42 is carried upon the post 70 and is operable in any desired manner as by a block signal system at present employed.

Assuming the invention to be in the position shown in Figs. 1 and 2, with the wheels 75 43 of an approaching train ready for contact with the trip 30 with the lever 28 as shown in Fig. 3, said lever 28 will be operated as shown in Fig. 4, with the wheel 43 engaging the trip to shift the same during 80 which movement the lever 28 is lowered against the tension of the spring-pressed pin 31 and forwardly projected to rotate the disk 25 upon the bearing 26 and to retract the link 27 connected to the disk 22 which motion is simultaneously communicated to the shafts 34 by the link connection 23 between the disks 22, and the belt connections 36 between the pulleys 35 and 37, and against the tension of the counterweights 13. The gates 90 will be lowered to the position illustrated in Fig. 6, and maintained in substantially lowered position against the force of the counterweights 13 as long as the train travels over the trips 30, while the gates will still 95 be maintained lowered and closed until the last wheel of the last car passes over the forward trip as illustrated in Fig. 6. As soon as the train completely passes the operating trips the counterweights 13 will assert their 100 force and restore the crossing arms 12 to the vertical position shown in Fig. 1, at which time traffic across the track between the crossing arms will be permitted.

The device is equally practicable and operative when the gears 38 are employed in lieu of the belt drive 36 and the crank shaft 39, when employed in lieu of the shaft 18 with the disk 22 thereon will also function in as efficient a manner. The crossing arms 110 are operable with trains passing in either direction, and while the form of the invention herein shown and described is what is believed to be the preferable embodiment thereof, it is nevertheless to be understood 115 that minor changes may be made in the form, combination and arrangement of parts without departing from the spirit and scope of the invention as claimed.

What I claim as new and desire to secure 120 by Letters Patent is:—

A device of the class described comprising in combination with a railroad track, a housing extending longitudinally thereof and beneath the same, vertical casings positioned 125 at opposite sides of the track, cross bars journaled thereon, operating means for said arms and located within said casings, tubular members connecting said housing and casings together, shafts extending through said 130

tubular members and having one of their ends connected to the respective cross arm operating means, the free ends of said shafts journaled in one side wall of the housing, 5 disks secured to said shafts and located within said housing, links having one of their ends pivoted to said disks, the free ends of said links extending longitudinally through

and out of the end walls of said housing, trips on the free ends of said links, said 10 trips positioned above and in abutting engagement with the tracks, and resilient means supporting said means above said tracks.

In testimony whereof I affix my signature.
ANTHONY NAMOLICK.
